UNITED STATES PATENT OFFICE.

FRIEDRICH KNÜTTEL, OF CHARLOTTENBURG, GERMANY.

GRAIN-STEEPING TROUGH OR CISTERN.

SPECIFICATION forming part of Letters Patent No. 622,051, dated March 28, 1899.

Application filed December 9, 1898. Serial No. 698,742. (No model.)

To all whom it may concern:

Be it known that I, FRIEDRICH KNÜTTEL, engineer and managing director, a subject of the King of Prussia, Emperor of Germany, and 5 a resident at Charlottenburg, in the Kingdom of Prussia, German Empire, have invented new and useful Improvements in or Connected with Grain-Steeping Troughs or Cisterns, of which the following is a specification.

10 Where grain-steeping troughs or cisterns are used, water may be employed by a well-known method either during the soaking process or after its completion for simultaneously flushing the grain away into another receiver 15 and washing it. To this end compressed air is admitted into the lower end of a tube erected within the steeping trough or cistern, whereby a mixture of air, water, and grain is caused to issue from the upper end of such 20 vertical or ejector tube, so that the grain, along with the water, may be conducted into another receiver. What has hitherto stood in the way of the more general adoption of this grain-washing process was the great consumption 25 of water which it involved, for it has been found in practice that the amount of work yielded by the siphon arrangement must decrease at a rapid rate and eventually dwindle away to naught unless the water in 30 the trough or cistern is maintained at a level representing not less than about sixty per cent. of the length of the vertical tube—that is, of the height to which the grain is to be lifted. The consequence is that in order to 35 remove all the grain remaining in the steeping trough or cistern a sufficient quantity of water has to be superadded to raise the water-level to at least the height above mentioned.

The improved arrangement according to 40 this invention admits of a lower situation of the minimum water-level in the trough or cistern, such minimum becoming in fact reducible almost at will, and of a proportionate saving in the quantity of water required. 45 This is accomplished by providing the lower end of the steeping trough or cistern, which is generally of conical form, with a cylindrical extension of small diameter and inserting the correspondingly-lengthened ejector-tube into 50 such extension.

In the accompanying drawings, Figures 1

and 2 represent vertical sections of one form of a steeping trough or cistern constructed in accordance with this invention, it being shown in Fig. 1 as it is during the steeping or soaking process, while Fig. 2 illustrates its condition at the end of the washing stage.

To the conical bottom of the trough or cistern *a*, which is provided with an overflow at *a*⁰, there is fitted the cylindrical extension *b*, 60 the lower end of which is provided with a compressed-air tube or nozzle *c*. The water-supply tube *a'* is situated near the apex of the conical bottom of the trough or cistern, at which point there is also provided a valve *d*, serving to keep the extension-cylinder *b* separate from the steeping trough or cistern proper. This valve is preferably rigidly connected with the ejector-tube *e*, so that such tube can be made use of as a handle for controlling the valve. During the soaking process the valve *d* is kept closed, as shown in Fig. 1; but for the purpose of flushing the grain away into another receiver the tube *e* is slightly lifted, as shown in Fig. 2, so that the 75 grain slides down into the cylinder *b* and is carried upward as the compressed-air-inlet tube comes into operation. In Fig. 2 there is indicated the lowest water-level required to keep up this siphon action, while the point 80 that such water-level should reach, where (as in the arrangement heretofore adopted) the ejector-tube does not extend beyond the apex of the conical bottom, is indicated by the dotted line. The difference between the two 85 levels represents the minimum saving of water effected by the arrangement according to this invention, a saving which may be increased, as will be readily understood, by still further extending the cylinder *b* and ejector-tube *e* in the downward direction.

What I claim, and desire to secure by Letters Patent of the United States, is—

1. In a grain-steeping trough or cistern, the combination of a trough with an ejector-tube 95 within the trough, an extension at the lower end of the trough within which the ejector-tube extends, and compressed-air tube or nozzle, substantially as and for the purposes hereinbefore set forth.

2. In a grain-steeping trough or cistern, the combination of a trough with an ejector-tube

within the trough, an extension at the lower end of the trough within which the ejector-tube extends, a valve connected with the ejector-tube which valve closes the extension against the trough, and compressed-air tube or nozzle, substantially as and for the purposes hereinbefore set forth.

In testimony whereof I have hereunto set my hand in presence of two subscribing witnesses.

FRIEDRICH KNÜTTEL.
